UNITED STATES PATENT OFFICE.

JAMES P. GARDNER, OF CHICAGO, ILLINOIS.

MACHINE FOR TREATING LIMBS.

1,354,248.

Specification of Letters Patent. Patented Sept. 28, 1920.

Application filed January 27, 1919. Serial No. 273,349.

To all whom it may concern:

Be it known that I, JAMES P. GARDNER, a citizen of the United States, residing at Chicago, in the county of Cook and State of Illinois, have invented certain new and useful Improvements in Machines for Treating Limbs, of which the following is a specification.

This invention relates to a machine which is adapted to give massaging or kneading treatment, and is especially adapted for giving such treatment to the limbs of a person. The desirability of giving massage or manipulating treatment to the limbs of a person after such limbs have been injured, and during the reconstruction process, is becoming well recognized. This is particularly true in connection with arms or legs which have been broken or dislocated, or which may have been more or less paralyzed. While manual manipulation is beneficial, it is more or less inefficient on account of the strength required and the desirability of long continued manipulation or massage. Furthermore, manual manipulation, which depends upon the strength and skill of the masseur, cannot be regulated or adjusted in the same way as is possible with machines for this purpose.

The objects of the present invention are, to provide a machine which can be made comparatively small and inexpensively, and which will serve to effectively massage or knead the arms or legs of a person; to provide a machine of this character which may be accurately adjusted for varying the pressure; and, in general, to provide such an improved apparatus as will be described more fully hereinafter.

In the accompanying drawings illustrating this invention:

Figure 1 is a side view;

Fig. 2 is a rear elevation;

Fig. 3 is a plan view; and

Fig. 4 is a sectional plan view showing the lower portion of the machine.

As illustrated in these drawings, 5 represents an upright frame having front posts 6 and rear posts 7. These posts are connected, adjacent to the lower ends thereof, by means of a bed-plate or table 8, having hollow lugs 9 at the corners, which fit over the posts 6 and 7. The posts are also connected by a bracket or frame member 10, which is substantially U-shaped and is provided with lugs 11 which fit over the upper

ends of the posts 6, and with lugs 12 which fit over the posts 7. These lugs are secured to the posts in any well known manner in order to make a rigid frame construction. 60 The cross-piece 13 is provided with lugs 14 which fit over the upper ends of the posts 7 and are secured thereto, thus completing the general frame structure.

The bracket 10 has bearings 15 and 16 respectively for the shafts 17 and 18, which extend across the machine, the shaft 18 being provided with suitable means for adjustment, such as the adjusting screws 19. Drums or pulleys 20 and 21 are mounted on 70 the shafts 17 and 18 and carry a relatively wide endless belt 22. These pulleys may be fixed to their respective shafts, or the shafts may be stationary and the pulleys turn thereon. The drum or pulley 20 is driven 75 by a driving pulley 23, which may be made integrally therewith or secured thereto, and is driven by a belt 24.

A second bracket 25, which is similar in shape to the bracket 10, is provided with 80 lugs or bearings 26 which slidably engage the posts 7. This bracket has a bearing 27 at the center of the rear cross-piece which is engaged by the lower end of an adjusting screw 28. The cross-piece 13 has a central 85 threaded aperture 29 for the screw, so that as this screw is turned by means of the hand wheel 30, the bracket 25 will be moved up or down.

The bracket 25 supports the shafts 31 and 90 32 which carry drums or pulleys 33 and 34, which are supplied with an endless belt 35 similar to the lower belt arrangement just described. The pulley 33 is turned by a 95 driving pulley 36, which is also actuated by the belt 24.

Any suitable means may be utilized for driving the belt 24. In the present instance, the machine is illustrated as being driven by a motor 37. This motor is 100 mounted on the bed or table 8 and drives a cross-shaft 38 by means of any suitable reduction gearing, such as indicated by the worm 39 and worm gear 40, which gears are mounted in the gear box 41. This box 105 is preferably integrally formed with the bed or table 8 in the manner indicated. The shaft 38 carries a driving pulley 42, which drives the belt 24. It will be seen that as the bracket 25 is moved up and down, take-up means must be provided for adjusting the belt. Such means is furnished by the

idler pulley 43, which is mounted on an arm 44 which is pivotally mounted on the bearing for the shaft 38. An adjustable weight 45 serves to regulate the tension on the belt, but it will be observed that any other suitable take-up mechanism may be utilized.

The belt 22 carries the massaging or kneading devices, which may be of any suitable form or character. In the present instance, it is provided at intervals with bearings 46 which support the reduced ends of rollers 47, which rollers extend substantially across the full width of the belt. These rollers may be made of any suitable material, but I have found that wooden rollers are satisfactory for such purpose. The belt 35 is also provided with bearings 48 for rollers 49, which are similar to the devices just described.

While the size of this machine may be varied, it will be better understood from the dimensions as actually designed. The rollers 47 in this particular construction are about one inch in diameter and eight inches long. The drums or pulleys supporting the roller belts are about four inches in diameter, and the supporting shafts are about ten-inch centers. The opening between the upper and lower sets of rollers is sufficient so that it may be adjusted to receive the arm or leg of a person, which will ordinarily be extended through from the front of the machine; and the upper bracket is given a slight pitch so as to allow for the taper or reduction in the size of the limb inserted in the machine. It will also be noted that the upper bracket may be brought sufficiently close to the lower bracket so that the hand or wrist may be massaged.

The roller belts in this instance are shown as being driven in opposite directions, or so that adjacent portions of the two belts move in the same direction, but, of course, the belts may be driven in the same direction, if desired, by changing the driving belt 24. The belts may be driven continuously, or their direction may be reversed by utilizing a reversing motor, or the massage belts may be reciprocated by the use of such motor or any suitable reciprocating mechanism (not shown).

When the machine is to be used, for instance, in massaging an arm, the arm will be inserted from the front of the machine, and on account of the frame being open at the back, the hand may be projected through the frame so that the rollers may be brought to engage with any part of the arm desired. It will also be noted that the leg may be massaged in the same manner, the foot being projected through the back of the frame. It will also be seen that the limb may be inserted transversely so that

the rollers will move across the limb instead of longitudinally, and by adjusting the tension on the belts, the rollers may be brought more or less around the limb. For this treatment, resilient or yielding adjustment devices may be provided, but the belts 22 and 35 will ordinarily be sufficiently flexible and yielding so that the rollers may be brought to conform to the circumference of the limb.

It will be noted that various changes may be made in the arrangement of parts and details of construction in order that the machine may conform to different conditions or uses, and, therefore, I do not wish to be limited to the exact construction herein shown and described, except as specified in the following claims, in which I claim:

1. In a machine for treating limbs, the combination of a frame, including two vertical posts, a lower horizontally arranged belt provided with massage devices, carried by said frame, a vertically movable bracket mounted on said posts, an upper substantially horizontally arranged belt carrying massaging devices, mounted in said bracket, means for driving said belts, and means for adjusting the upper belt vertically.

2. In a massage machine, the combination of a frame, including front and rear posts, the rear posts extending upwardly above the front posts, a frame member connecting the posts at the top of the front posts, rollers mounted in said frame member, a belt carried by said rollers, massage devices mounted on said belt, a bracket slidably mounted on said rear posts above said belt, rollers mounted in said bracket, a belt carried by said rollers, massage devices on said last-named belt, means for driving said belts and a screw for adjusting said bracket.

3. In a massage machine, the combination of a frame, a massage belt mounted horizontally in said frame, a second massage belt arranged above the first-named belt, means for vertically adjusting said second-named belt, pulleys for driving said belts, a driving pulley, a driving belt from said pulley to the driven pulleys, an idler for taking up the slack in the driving belt, and means for turning said driving pulley.

4. In a massage machine, the combination of a frame, a horizontally arranged massage belt mounted in said frame, a second horizontally arranged belt mounted above said first-named belt with a space between them, means for adjusting one of said belts bodily with respect to the other belt, pulleys for driving said belts, a driven pulley, a driving belt from the driving pulley to the driven pulleys, and means for turning said driving pulley.

5. In a machine of the character set forth, the combination of a substantially horizon-

- tal massage belt, a second massage belt mounted above the first-named belt with a space between them, means for adjusting the second belt bodily toward and away from the first belt whereby a limb may be inserted between the belts and project beyond them, and means for actuating said belts. 5
6. In an apparatus of the character set forth, the combination of a horizontally ar- 10 ranged massage belt, a second massage belt arranged above the first-named belt and at an angle thereto, means for adjusting the belts bodily with respect to each other, and automatically adjustable means for driving 15 said belts.
7. In a machine for treating limbs, the combination of a frame, drums mounted in said frame, a belt carried by said drums, rollers mounted on said belt, a pulley for 20 driving one of said drums, a bracket mounted on said frame above said belt, means for adjusting said bracket vertically, drums carried by said bracket, a belt around said drums, rollers mounted on said belt, a pulley 25 for turning one of said drums, a motor, a driving pulley driven by said motor, a swinging arm, an idler pulley carried by said arm, a driving belt rove around said pulleys, and means for adjusting the tension 30 on said idler pulley.
8. In a machine of the character set forth, the combination of vertically arranged posts, a table carried by said posts, a top frame member connecting said posts, drums car- 35 ried by said frame member, a belt around said drums, bearings on said belt, transverse rollers carried by said bearings, a pulley for driving said belt, a cross-piece at the top of the two rear posts, a vertically adjustable bracket carried by said rear posts, a screw 40 coacting with said cross-piece for adjusting said bracket, drums carried by said bracket, a belt around said drums, bearings on said belt, rollers carried by said bearings, a pulley for driving said last-named belt, a driv- 45 ing pulley mounted adjacent to the table, a motor mounted on said table, reducing gear- 50 ing between the motor and driving pulley, a driving belt from said driving pulley to the pulleys for driving said belts, and an automatic take-up for said driving belt.
9. In a massage machine, the combination of a horizontally movable massage device, a second horizontally movable massage device positioned above the first-named device and 55 between which and the first-named device the member to be massaged is positioned, means for adjusting one of said devices bodily toward and from the other device, and means for actuating said devices. 60
10. In a massage machine, the combination of a horizontally movable massage device, a second horizontally movable massage device positioned above the first-named device, means for actuating said devices, and 65 means for adjusting the entire devices relatively to each other.

JAMES P. GARDNER.
